INVENTOR.

William E. Nickerson

UNITED STATES PATENT OFFICE.

WILLIAM E. NICKERSON, OF CAMBRIDGE, MASSACHUSETTS.

FLUID SPEED-REGULATOR FOR ELEVATORS.

SPECIFICATION forming part of Letters Patent No. 403,436, dated May 14, 1889.

Application filed February 5, 1889. Serial No. 298,559. (No model.)

To all whom it may concern:

Be it known that I, WILLIAM EMERY NICKERSON, of Cambridge, in the county of Middlesex and State of Massachusetts, have invented certain new and useful Improvements 5 in Fluid Speed-Regulators for Elevators, of which the following, taken in connection with the accompanying drawings, is a specification.

10 My invention consists in combining with the carriage of an elevator a retarding-rope, the velocity of motion of which is governed by the descent of a piston, said piston working in a cylinder full of fluid, which may be 15 open at the top, as it requires no stuffing-box or appliance to prevent leakage, and governed in its velocity by fluid-passages and automatic valves.

15 My invention is embodied in the mechanism shown in the accompanying drawings, in which—

Figure 1 is an elevation showing such parts as are required to illustrate the application of my device to an elevator. Fig. 2 is a vertical section taken through the retarding-cylinder, also showing the parts directly connected with the cylinder.

In Fig. 1, C represents the elevator-carriage, and K the hoisting-rope, which passes 30 over the pulley K' and down to the hoisting-engine.

R, Fig. 1, is a rope for retarding or regulating the velocity of descent of the elevator-carriage. This rope passes over the fixed 35 pulley R', down under the fixed pulley R², and over the moving pulley R³, attached to the head of the piston-rod P, thence to the fastening R⁴ at the head of the cylinder D.

The cylinder D has at its base B a fixed 40 pulley, R², and at its upper end wing-pieces H H, which serve to hold and support two posts, H' H', which are united at the tops by the cross-piece H², to which they are firmly connected. The posts H' H' serve as guides 45 for the piston cross-head P³. Said piston cross-head also serves as a support for the housing P² P', Fig. 2, for the pulley R³.

D' is a piston attached to the lower end of the rod P. (See Fig. 2.) The piston D' has 50 openings d d, which are closed by the sliding valve D². The sliding valve D² may be made so much smaller than the cylinder as to allow a free passage of fluid between it and the cylinder; or it may have openings, as shown at 55 e e, Fig. 2.

The valve in its normal position does not affect the passage of fluid through the openings d d in the piston D', and only acts when the velocity of descent of the elevator-carriage is so great as to force the piston downward so rapidly as to create an upward flow through the piston of sufficient force to cause the valve D² to slide up against the piston and close the openings d d. This action will check the descent of the piston to the desired extent. The descent of the piston can be still further regulated by the valve V in the pipe D⁴, which communicates between the lower end of the cylinder and the upper part, as shown in Fig. 2. The piston P is drawn 60 up by the retracting-weight P⁶, attached to the rope P⁵, which passes over the pulley P⁴. This weight also may serve partially or wholly 65 the purpose of the ordinary counterbalance-weight usually used in elevators. 70

75 The operation of my device is as follows: As the elevator-carriage C begins to descend, it, acting through the retarding-rope R and the moving pulley R³ at the top of the piston P, gives a motion (also descending, but with 80 one-half the velocity of the carriage) to the piston D', and so long as the velocity is a safe one the valve D² will remain down and off from its seat on the under side of the piston; but if the rate of speed exceed that of 85 safety, or the rate at which it is desired that the carriage shall move, then the valve D² closes onto the piston D' and checks the speed. 90

The sliding valve D² may be omitted and an automatic valve be placed in the pipe D⁴, if desired.

It will be observed that the pipe D⁴ is not an essential feature of my device.

I claim—

In an elevator, the combination of the carriage C, retarding-rope R, piston D, having at the top of its rod P a pulley, R³, adapted to receive the retarding-rope R, and valve D², with the cylinder D and retracting-weight 100 P⁶, substantially as and for the purpose set forth.

In testimony whereof I have signed my name to this specification, in the presence of two subscribing witnesses, on this 2d day of February, A. D. 1887.

WILLIAM E. NICKERSON.
